HYDRAULIC UNLOADING AND
CIRCULATING DEVICE
Leonard L. Huckaby, Rte. 2, Box 115,
Santa Paula, Calif.
Filed June 7, 1963, Ser. No. 286,402
6 Claims. (Cl. 103—221)

This invention relates generally to devices for use in wells and more particularly, to an improved hydraulic unloading and circulating device adapted to be inserted within the threaded joint of a well tool supported on the end of a pipe string for passing fluid from the exterior of the tool to the interior thereof in response to a pulling force by the pipe string.

The preferred embodiment of the device of this invention is best adapted for use when it is desired to pull a pump or remove the same from an oil well and for purposes of the present specification, the tool will be described in conjunction with such an operation.

In order to pump oil from a well in which casing has been set, the casing is perforated by a suitable gun at those levels in which oil has been indicated to exist. After the casing has been perforated, a pumping tube is lowered on the end of the conventional drill pipe string to this particular level and within the pumping tube itself there is then lowered a pumping apparatus. The lower interior of the pumping tube terminates in an annular seat adapted to receive in sealing relationship the lower end of the pumping apparatus. The pumping apparatus itself is operated by sucker rods which pass up through the pumping tube and pipe string and are reciprocated to operate a plunger within the pumping apparatus. Oil may thus be pumped through the perforations in the casing and up past the lower annular seat of the pumping tube, through the pumping apparatus, and thence upwardly through the surface of the well.

After pumping has been completed or if it is desired to change the pump or repair it, it is necessary to unseat the lower end of the pumping apparatus from the annular seat defined by the pumping tube. Since, however, the pumping apparatus as well as the tube itself is filled with oil throughout a considerable length, whereas the surrounding fluid in the casing exterior of the pumping tube may be a relatively low level, there exists a very large pressure differential rendering it extremely difficult to unseat the pump from the annular seat of the pumping tube. In fact, the sucker rods themselves through which the pulling force is applied to the pump may very well break before sufficient force is applied to unseat the pump.

The foregoing condition may be overcome if the fluid within the pipe string and surrounding the pumping apparatus within the pumping tube could be passed in a reverse direction through the pump and out the lower end thereof past the seat to the exterior of the pumping tube. If the fluid could be passed in this manner, the large hydrostatic head created within the pumping apparatus and pipe string could be "dumped" into the surrounding area of the pumping tube and thus equalize with that outside pressure so that removal of the pumping apparatus from the annular seat could be very readily achieved.

It would be desirable in a tool of the foregoing type that the hydraulic unloading of the fluid within the pipe string to the exterior of the tool would only operate in the event a force greater than that which might damage the sucker rods would be required to unseat the pumping apparatus.

In other instances of pumping operations, the pump tool itself may become stuck in the bore hole and in such event, it would be desirable to remove at least a portion of the tool so that suitable fishing equipment could be brought in to remove the stuck portion.

2

With the foregoing considerations in mind, it is a primary object of this invention to provide a hydraulic unloader and circulating device which is responsive to a predetermined pulling force to pass fluid within the surrounding pumping tube to the interior of the tool and out the lower end so that unseating of the pump is greatly facilitated.

More particularly, it is an object to provide a hydraulic unloading and circulating device adapted to be inserted at a threaded joint of a well tool without modifying the tool and which includes means enabling separation of two parts making up the device itself to the end that should a portion of the tool become stuck, it is a simple matter to remove the remaining portion leaving an end readily adapted to cooperate with fishing equipment.

Still other objects of this invention are to provide a hydraulic unloader and circulating device adapted to be inserted in the threaded joint of a well tool, which will not disturb normal operation of the tool and yet enables equalization of the fluid pressure from about the exterior of the tool with the pressure of fluid exerted on the interior portion thereof.

Another object is to provide a device meeting the foregoing objects which is rugged in construction and reliable in operation.

Briefly, these and many other objects and advantages of this invention are attained by providing a sleeve cooperating with an inner cylinder partially telescoped within the sleeve. The inner cylinder itself includes a straight through fluid passage having a lateral port which, when the inner cylinder is in a first telescoped position, is encompassed by the sleeve so that no fluid can pass through the lateral port. However, when the inner cylinder is telescoped outwardly to a second position, the lateral port is exposed so that there is provided a passage for fluid from the exterior of the device to the interior straight through passage.

The lower end of the sleeve terminates in threads adapted to be threaded to the lower threads of a threaded joint in the oil well tool with which the device is to be used. The upper end of the inner cylinder, in turn, is threaded to a unique coupling in turn including threads for cooperation with the upper threads of the threaded joint of the tool. The coupling itself includes left hand threads cooperating with left hand threads on the upper end of the inner cylinder such that the device may be separated by rotation in a right hand direction of the pipe string without loosening any of the other joints. By this arrangement, should the lower end of the tool in question become stuck, it is a simple matter to remove the remaining portion of the tube by separating the coupling from the upper end of the inner cylinder. Suitable fishing equipment may then be lowered.

Normally, the inner cylinder is held with respect to the sleeve by shear pins so that a force in excess of a predetermined force is required to shear the pins and thus telescope outwardly the inner cylinder to expose the port. Accordingly, hydraulic unloading of fluid within a pipe string to the exterior of the tool by passing the fluid down inwardly to the tool is only effected in response to an upwardly pulling on the drill pipe string. When the device is used with a pumping apparatus, this predetermined force is less than that which would damage the sucker rods so that hydraulic unloading of fluid within the pipe string to facilitate unseating of the pump unit will be effected before any damage to the pump sucker rods is incurred.

A better understanding of the invention will be had by now referring to the preferred embodiment thereof as illustrated in the accompanying drawings, in which:

FIGURE 1 is a cross-section of a pumping unit posi-

tioned in an oil well bore hole for pumping oil therefrom;

FIGURE 2 is an enlarged elevational view partly broken away illustrating the hydraulic unloading and circulating device of this invention adapted to be inserted within a threaded joint of the tool shown in FIGURE 1; FIGURE 3 is a view similar to FIGURE 2, but illustrating the components of the device in a position to effect a hydraulic unloading operation; and,

FIGURE 4 is a perspective view of a clutching arrangement employed with the device illustrated in FIGURES 2 and 3.

Referring first to FIGURE 1, there is shown an oil well bore hole 10 within which casing 11 has been positioned. As shown in the lower left hand portion of FIGURE 1, the casing 11 has been perforated as at 12 to admit oil from the surrounding formations to the interior of the casing. This oil is designated by the numeral 13. When pumping is required to remove the oil, the pressure of oil passing through the perforations 12 is not great and therefore the oil level within the casing 11 may be relatively low, such as indicated by the level line 13'.

To pump the oil 13 to the surface, there is first lowered a pumping tube 14 terminating at its lower inner end in an annular seat 15. This seat 15 in turn is arranged to cooperate with a pumping apparatus including a pump barrel 16. The lower end of the pump barrel 16 seats in seating relationship on the seat 15 and includes a threaded joint as indicated at 17 generally relatively close to the seated end. Within the pump barrel 16, there is included a lower annular seat 18 and ball valve 19. A plunger 20 in turn is positioned above the ball 19 and itself includes at its upper end an annular seat 21 and a second ball valve 22. The upper end of the plunger 20 is coupled by a spider structure 23 to sucker rods 24 so that the plunger 20 may be moved in an up and down direction. Small ports 25 are provided at the upper end of the pump barrel 16 so that oil pumped up by the movement of the plunger 20 will pass upwardly to the surface of the bore hole through the pumping tube 14.

Thus, in the operation of the pump described in FIGURE 1, upward movement of the plunger 20 by pulling on the sucker rods 24 will result in the ball 19 unseating from the seat 18 and oil passing upwardly within the pumping barrel 16 above the ball 19. Subsequent downward movement of the plunger 20 will then close the ball 19 on the seat 18 and thus the oil entrapped will be forced past the ball 22 which will be unseated from the seat 21. The next upward movement of the plunger 20 will then lift this oil out through the openings 25 and up through the pumping tube 14 to the surface of the well.

When it is desired to remove the pump barrel 16, it is normal practice to simply pull on sucker rods 24 until the lower end of the barrel is unseated from the annular seat 15 of the pumping tube 14. The entire pumping apparatus may then be raised to the surface of the bore hole. However, since the pressure exerted on the pump barrel 16 by the hydrostatic head of oil within the pumping tube 14 is considerably greater than the pressure of the oil 13 within the casing 11, the pump barrel 16 is held by hydrostatic pressure on the seat 15. In other words, the pressure exerted up through the lower end of the pumping tube 14 past the annular seat 15 is very low since the height of the oil indicated by the level line 13' is relatively low, whereas the pressure on the upper side of the pump unit is extremely high because of the tremendous hydrostatic head of the oil extending to the surface of the bore hole.

If the aforementioned hydrostatic head of oil within the pumping tube 14 could be relieved by passing the oil within the tube to the exterior of the pumping apparatus, it would be very easy to unseat the pump barrel 16 from the annular seat 15.

In accordance with the instant invention, this hydraulic unloading is achieved by inserting a device in the threaded

joint 17 of the pump barrel 16. This device is illustrated in FIGURES 2 and 3, and as shown, includes a sleeve 26 terminating at its lower ends in threads 27 adapted to be threadedly connected to the lower threads of the joint 17 of the pump barrel 16 of FIGURE 1. Cooperating with the sleeve 26 is an inner cylinder 28 partially telescoped therein as shown and including an internal straight through passage 28'. Cylinder 28 terminates at its upper end in a coupling 29, the lower end of this coupling 29 having left hand threads 30 cooperating with left hand threads on the upper end of the inner cylinder 28. The upper end of the coupling 29 includes conventional threads 31 for threaded connection to the upper threads of the joint 17. By this arrangement, the device may readily be inserted within the joint 17 so as to constitute part of the pump barrel 16 without modifying the pump barrel.

As shown in FIGURE 2, the inner cylinder 28 is held longitudinally against telescoping movement with respect to the sleeve 26 as by shear pins 32 and 33 projecting laterally through the sleeve and partially into the exterior side walls of the cylinder. Further, there are provided O-rings such as indicated at 34 to seal off a lateral port 35 included in the straight through central passage 28' of the inner cylinder 28. Thus, when the sleeve 26 and cylinder 28 are in their telescoped positions illustrated in FIGURE 2, the port 35 is encompassed by the sleeve 26 and thus is blocked from passing any fluid.

The lower end of the inner cylinder 28 terminates in an enlarged flange 36 including a transverse channel 37. This structure as best shown in FIGURE 4, cooperates with a lower fitting 38 including a transverse projecting portion 39 adapted to be received in the channel 37 when the inner cylinder 28 is telescoped to its downward position, as illustrated in FIGURE 2. This clutch arrangement prevents relative rotation between the inner cylinder 28 and sleeve 26 when the inner cylinder is in its first telescope position as shown. The interior 40 of the sleeve receiving the lower end of the cylinder is of increased diameter to define an annular shoulder 41. This shoulder serves as a stop against the flange 36 to prevent separation of the cylinder and sleeve.

In operation, if the device of FIGURE 2 is threaded within the threaded joint 17, normal pumping operations can take place. However, when it is desired to remove the pumping unit as by unseating the same from the annular seat 15, an upward force is exerted on the sucker rods 24. If the force required to remove the pump is such that it may damage the sucker rods, the shear pins 32 and 33 will shear prior to this time to permit outward telescoping movement of the inner cylinder 28 with respect to the sleeve 26. The various components will then assume the positions as illustrated in FIGURE 3, wherein it will be noted that the port 35 is exposed above the sleeve 26.

When the portions of the device are in the positions illustrated in FIGURE 3, it will be immediately evident that fluid may now pass through the port 35 and down through the central passage and out the end past the annular seat 15 of the pumping tube illustrated in FIGURE 1. The fluid within the pumping tube 14 is passed to the exterior of the pumping tube and thus no longer exerts a large hydrostatic pressure on the pump barrel 16. It is thus a simple matter to unseat the pump barrel 16 and raise the unit to the surface of the bore hole.

If, for some reason, the shear pins 32 and 33 should not shear or outward telescoping movement is prevented, or if the lower end of the pump barrel 16 becomes stuck and it is desired to still remove the pump unit and effect a hydraulic unloading, the coupling 29 illustrated in FIGURES 2 and 3 may be used. Thus, the inner cylinder 28 will be telescoped inwardly until the clutch engages, thus preventing relative rotation between the sleeve 26 and inner cylinder 28. If now the upper end of the pump barrel 16 is caused to rotate in a normal clockwise direction, the left hand threads 30 described in FIGURE 2 will re-

sult in a separation of the coupling 29 from the upper end of the cylinder 28. After this separation, the upper end of the passage 28' in the cylinder 28 will be exposed to pass fluid downwardly past the seat 15 and thus effect the desired hydraulic unloading. The upper portion of the pumping unit may then be removed together with the coupling 29 and, subsequently, a suitable fishing tool lowered to engage the inner cylinder 28 and thence effect removal of the remaining portion of the tool.

From the foregoing description, it will be evident that a greatly improved hydraulic unloading and circulating device has been provided which will greatly facilitate the removal of pumping apparatus from a well bore by equalizing the hydrostatic pressures tending to hold the pumping unit on the annular seat 15 of the pumping tube. Further, it will be evident that in the event the tool should become stuck, the fact that the device illustrated in FIGURES 2 and 3 may be separated as a consequence of the use of the coupling 29 with left hand threads enables removal of at least a portion of the tool. Fishing of the remaining portion is then greatly facilitated as a consequence of the exposed end of the inner cylinder being available for cooperation with the fishing tools.

While the invention has been described in conjunction with a particular use in pumping operations, it should be understood that the device will find use in other applications without departing from the scope and spirit of the invention. The hydraulic unloading and circulating tool should therefore not be thought of as limited to the exact embodiment set forth merely for illustrative purposes.

What is claimed is:

1. A hydraulic unloading and circulating device for insertion in a threaded joint in a well tool to equalize fluid pressure between the interior and exterior of said tool in response to a pulling force on said tool, comprising, in combination: a sleeve threaded to the lower threads of said joint; an inner cylinder partially telescoped within said sleeve, the upper end of said cylinder being coupled to the upper threads of said joint, said inner cylinder having a straight through central passage including a lateral port encompassed by said sleeve when said inner cylinder is telescoped within said sleeve to a first given position and exposed above said sleeve when said inner cylinder is pulled outwardly from said sleeve to a second position; and, a coupling for coupling the upper end of said cylinder to the upper threads of said joint, said coupling having left hand threads on its lower end, said cylinder having left hand threads on its upper end to receive said coupling, the upper end of said coupling having right hand threads to receive said upper threads of said joint whereby the upper end of said straight through passage in said cylinder may be exposed by unthreading of said coupling therefrom upon rotation of the upper end of said tool in a right hand direction without loosening the remaining threaded joints in said device and tool.

2. A device according to claim 1, including clutch means adapted to be engaged when said cylinder is in said first position to prevent relative rotation between said sleeve and cylinder.

3. A hydraulic unloading and circulating device

adapted to be inserted in a threaded joint of a well tool connected to sucker rods and supported on the end of a pipe string through which said sucker rods extend for passing fluid from the exterior of said tool to the interior thereof in response to a pulling force by said sucker rods on said tool exceeding a predetermined value, said device comprising, in combination: an outer sleeve having lower threads for threaded connection to the lower threads of said joint; an inner cylinder having a lower end portion telescopically received in said sleeve, the upper end of said inner cylinder terminating in left hand threads; a coupling having left hand threads for connection to said upper end of said inner cylinder and right hand threads for threaded connection to the upper threads of said joint; said inner cylinder having a straight through fluid passage including a lateral port encompassed by said sleeve when said cylinder is in a first telescoped position in said sleeve; and holding means for holding said cylinder and sleeve in said first telescoped position and responsive to a pulling force greater than said predetermined value to release said cylinder and permit outward telescoping movement thereof from said sleeve to expose said port above said sleeve whereby fluid may pass into said port and to the interior of said tool.

25 4. A device according to claim 3, in which said holding means comprises lateral shear pins extending through said outer sleeve to project partially into the outer surface of said inner cylinder.

30 5. A device according to claim 4, in which right hand rotation of said sucker rods and the upper end of tool when the portion of said tool below said joint is held against rotation unthreads said coupling from the upper end of said inner cylinder to expose the upper end opening of said straight through passage whereby fluid may 35 pass from the exterior of said tool through said passage to the interior thereof.

35 6. A device according to claim 5, in which said sleeve includes an increased diameter internal portion defining an annular shoulder, said lower end of said inner cylinder being received in said increased diameter internal portion and including an annular flange having a transverse channel therein; and the lower end of said increased diameter portion including an upwardly projecting transverse portion adapted to be received in said channel when said inner cylinder is in said first position to hold said inner cylinder and sleeve against rotation relative to each other when said inner cylinder is in said first position, said annular shoulder being adapted to engage the upper side of said annular flange when said inner cylinder is telescoped 40 to its second position to prevent complete disengagement of said inner cylinder from said sleeve.
